UNITED STATES PATENT OFFICE.

JOSEPH PEYSER, OF MOUNT VERNON, NEW YORK.

SEAMING MECHANISM.

Application filed August 6, 1924. Serial No. 730,412.

This invention relates to seaming mechanism for uniting containers and covers, and has for its main object and feature the provision of simple and easily adjustable means for actuating the seaming means, particularly, though not exclusively, to be used in connection with non-round containers, and so arranged that the seaming tool may be driven at all times notwithstanding the in-and-out movement of the seaming tool toward and away from the work.

In the accompanying drawings the invention is disclosed in several concrete and now preferred forms in which:

15 Fig. 1 is a vertical section through a seaming mechanism embodying the invention in a device in which the work stands still and the seaming tools travel around the work in an orbit.

20 Fig. 2 is a horizontal sectional view on the plane of line 2—2 of Fig. 1.

Fig. 3 is a horizontal sectional view on the plane of line 3—3 of Fig. 1.

25 Fig. 4 is a vertical sectional view on the plane of irregular line 4—4 of Fig. 2.

Fig. 5 is a perspective view of the floating member that rotates the seaming tool.

Fig. 6 is a perspective view of the sleeve and plate that carries the seaming tool.

30 Figs. 7, 8 and 9 are views similar to Fig. 3, but with some of the parts removed, showing the movement of the floating member during the operation of the device.

35 Fig. 10 is a vertical sectional view of a seaming mechanism showing a modified form of the invention in which the work rotates.

Referring to Figs. 1 to 9 inclusive, 1 indicates a chuck to engage cover 2 of container 3. In the present instance this chuck is non-rotating. The container here selected for illustration is non-circular and specifically substantially square as indicated in outline in Figs. 3, 7, 8 and 9. The outline of the seaming tool 4 is complementary to that of the container. The problem that this invention seeks to solve in an effective and simple way is to effect relative movement between the work and the seaming tool, to rotate the seaming tool and to impart an in-and-out movement to the seaming tool without bringing the elements of the driving mechanism out of mesh, the parts being also readily adjustable and removable.

55 Of course one may say that that is the problem of all seaming mechanism and it is

solved readily enough where the container and seaming tool are both round. It is not such a simple matter to accomplish this when the container and seaming tool are non-circular, and this invention is more particularly designed to meet the requirements of non-circular containers, although I wish it to be distinctly understood that the invention can be used in connection with circular containers and tools.

In the form shown in Figs. 1 to 9 inclusive the relative movement between the work and seaming tool or between the chuck and seamer head is obtained by causing the work to stand still and the seamer head to travel in an orbit around the work. As shown in the drawings chuck 1 is mounted on stationary shaft 5 and keyed to the same shaft is a gear 6 concentric with the chuck. 7 indicates a seamer head mounted concentric with shaft 5 and driven in any suitable way as by means of bevel gears 8 and 9. 10 is a cam concentric with the seamer head, chuck and shaft 5.

The number of seaming tools may vary, but since they are constructed alike a description of one will suffice. 11 indicates a support carried by the head, and extending eccentrically through said support is a crank shaft 12 having at one end an arm 13 provided with a cam roll 14 engaging cam 10. At its other end said crank shaft is provided with a crank pin 15 carrying the seaming tool 4. From this it will be understood that rotation of cam 10 (here effected by sleeve 16 and bevel gears 17 and 18) will cause the crank shaft to rock and will move the seaming tool toward or away from the work. The means for rotating the seaming tool are as follows:

Mounted loosely on support 11 is a gear 19 that is in constant mesh with gear 6 on shaft 5. Interposed between the seaming tool and gear 19 is a floating member 20 and this floating member forms by means of pins and slots, the driving connection between gear 19 and seaming tool 4 so that the latter is constantly rotated from the former notwithstanding rocking movement of the crank shaft. In the specific form here disclosed these parts are constructed as follows: Mounted on crank pin 15 is a sleeve member 21 having a circumferential plate 22. Seaming tool 4 is secured to the underside of plate 22 by means of screws 23 or otherwise. 24 is a screw the head of which supports the lower end of sleeve 21 and is tapped into

the end of crank pin 15. In the upper surface of plate 22 are two radial slots 25. Resting on this plate is floating member or disc 20 which at its underside is provided with shoes 26 to engage slots 25. In its upper surface said disc has two radial slots 27, at right angles to shoes 26, and engaging with these slots are two shoes 28 carried by gear 19. It will now be understood that rotation of the seamer head carries support 11 in an orbit around the chuck and that by reason thereof gear 6 rotates gear 19, and, there being a difference in speed between seamer head 7 and cam 10, the crank shaft 15 will be rocked to thereby bring its crank pin, and therefore the seaming tool, toward or away from the work. Rotation of gear 19 will be transmitted to floating member 20, and the latter will, in turn, drive plate 22 and seaming tool 4. The floating member will, as indicated in Figs. 7, 8 and 9, accommodate itself by sliding with respect to shoes 28 of gear 19 and with respect to slots 25 of plate 22. The positions shown in Figs. 7, 8 and 9 vary by one-eighth of a revolution and the seaming tool is supposed to be traveling in an orbit around the work in the direction indicated by the arrows. For the sake of convenience and to preserve the symmetry 30 of the drawings on the sheet the orbital movement of the seaming tool around the work is represented by varying the position of container 3.

If it is desired to replace seaming tool 4, or any of the elements from gear 19 down to the seaming tool, it is only necessary to remove screw 24. Support 11 is seated in a circular opening 29 in the seamer head and is provided with arms 30 beneath said seamer head. Said arms have curved slots 31 through which extend bolts 32 into the seamer head. Carried by the seamer head is a bracket 33 in which is a rotatable member 34 in threaded engagement with one of the arms 30. It will be apparent, bolts 32 having been loosened, that, by turning member 34, support 11 will be turned in recess 29. This will alter the angular relation of arm 13 between crank shaft 12 and cam 10 and will adjust the position of the crank pin to move the seaming tool nearer to or farther away from the work so as to vary the tightness of the seam.

In Fig. 10 is shown a modification in that chuck 1 and gear 6 are mounted upon a shaft 35 that rotates, motion being imparted thereto by pulley 36. Seamer head 7 is here stationary and cam 10 is driven by means of bevel gears 37 and 38. The seaming tool and its supporting means are the same as in the first form of the invention.

I claim:

1. Seaming mechanism comprising: a crank pin, a seaming tool carried by the crank pin, a support, a crank shaft extend-

ing through said support and carrying the pin, a gear on the support, means for turning the crank shaft back and forth, and driving means between the gear and the seaming tool to rotate the latter from the former at all times notwithstanding movement of the crank shaft. 70

2. Seaming mechanism comprising: a crank pin, a seaming tool carried by the crank pin, a support, a crank shaft extending eccentrically through said support and carrying the pin, a gear concentric with the support, means for turning the crank shaft back and forth, and driving means between the gear and the seaming tool to 75 rotate the latter from the former at all times notwithstanding movement of the crank shaft.

3. Seaming mechanism comprising: a crank pin, a seaming tool carried by the crank pin, a support, a crank shaft extending through said support and carrying the pin, a gear on the support, means for turning the crank shaft back and forth, a floating member on the crank pin between the gear and the seaming tool, and a pin and slot connection between the gear and the floating member and between the floating member and the seaming tool. 85 90

4. Seaming mechanism comprising: a crank pin, a seaming tool carried by the crank pin, a support, a crank shaft extending eccentrically through said support and carrying the pin, a gear concentric with the support, means for turning the crank shaft back and forth, a floating member on the crank pin between the gear and the seaming tool, and a pin and slot connection between the gear and the floating member and between the floating member and the seaming tool. 95 100 105

5. Seaming mechanism comprising: a crank pin, a seaming tool carried by the crank pin, a support, a crank shaft extending through said support and carrying the pin, a gear on the support, means for turning the crank shaft back and forth, and a floating member on the crank pin slidably connected to the gear and to the seaming tool to drive the latter from the former at all times notwithstanding movement of the crank shaft. 110 115

6. Seaming mechanism comprising: a crank pin, a seaming tool carried by the crank pin, a support, a crank shaft extending eccentrically through said support and carrying the pin, a gear concentric with the support, means for turning the crank shaft back and forth, and a floating member on the crank pin slidably connected to the gear and to the seaming tool to drive the latter from the former at all times notwithstanding movement of the crank shaft. 120 125

7. Seaming mechanism comprising: a can chuck, a seamer head, said chuck and 130

- head having a movement one with respect to the other, a cam concentric with the chuck and having a movement relative to the head, a gear concentric with the chuck, 5 a support on the head, a crank shaft extending through said support and actuated from the cam, a crank pin carried by the crank shaft, a gear on the support meshing with the first gear, a seaming tool carried 10 by the crank pin, and driving means between the second mentioned gear and the seaming tool to rotate the latter from the former at all times notwithstanding movement of the crank shaft.
- 15 8. Seaming mechanism comprising: a can chuck, a seamer head, said chuck and head having a movement one with respect to the other, a cam concentric with the chuck and having a movement relative to the head, a gear concentric with the chuck, a support 20 on the head, a crank shaft extending through said support and actuated from the cam, a crank pin carried by the crank shaft, a gear concentric with the support and meshing with the first gear, a seaming tool carried by the crank pin, and driving means between the second mentioned gear and the seaming tool to rotate the latter from the former at all times notwithstanding movement of the crank shaft.
- 25 9. Seaming mechanism comprising: a can chuck, a seamer head, said chuck and head having a movement one with respect to the other, a cam concentric with the chuck and having a movement relative to the head, a gear concentric with the chuck, a support 30 on the head, a crank shaft extending through said support and actuated from the cam, a crank pin carried by the crank shaft, a gear concentric with the support and meshing with the first gear, a seaming tool carried by the crank pin, and driving means between the second mentioned gear and the seaming tool to rotate the latter from the former at all times notwithstanding movement of the crank shaft.
- 35 10. Seaming mechanism comprising: a can chuck, a seamer head, said chuck and head having a movement one with respect to the other, a cam concentric with the chuck and having a movement relative to the head, a gear concentric with the chuck, a support 40 on the head, a crank shaft extending through said support and actuated from the cam, a crank pin carried by the crank shaft, a gear on the support meshing with the first gear, a seaming tool carried by the crank pin, a floating member on the crank pin between the second mentioned gear and the seaming 45 tool, and a pin and slot connection between the second mentioned gear and the floating member and between the floating member and the seaming tool.
- 50 11. Seaming mechanism comprising: a can chuck, a seamer head, said chuck and head having a movement one with respect to the other, a cam concentric with the chuck and having a movement relative to the head, a gear concentric with the chuck, a support 55 on the head, a crank shaft extending through said support and actuated from the cam, a crank pin carried by the crank shaft, a gear on the support meshing with the first gear, a seaming tool carried by the crank pin, and a floating member on the crank pin slidably connected to the second mentioned gear and to the seaming tool to drive the latter from the former at all times notwithstanding movement of the crank shaft.
- 60 12. Seaming mechanism comprising: a can chuck, a seamer head, said chuck and head having a movement one with respect to the other, a cam concentric with the chuck and having a movement relative to the head, a gear concentric with the chuck, a support 65 on the head, a crank shaft extending through said support and actuated from the cam, a crank pin carried by the crank shaft, a gear concentric with the support and meshing with the first gear, a seaming tool carried by the crank pin, and a floating member on the crank pin slidably connected to the second mentioned gear and to the seaming tool to drive the latter from the former at all times notwithstanding movement of the crank shaft.
- 70 13. Seaming mechanism comprising: a support, a crank shaft extending through the support, a crank pin on the crank shaft, a gear on the support, a sleeve member on the crank pin, a circumferential plate carried by the sleeve member, a floating member surrounding said sleeve between the gear and the plate, and having pin and slot connection with the gear and the plate, a seaming tool connected with the plate, and means for removably holding the seaming tool, plate and disc on the crank pin.
- 75 14. Seaming mechanism comprising: a seamer head, a cam, a support rotatably adjustable in the seamer head, a crank shaft extending eccentrically through the support, an arm connected to one end of the crank shaft, a cam roll on said arm to engage the cam, a crank pin connected to the other end of said crank shaft, and a seaming tool carried by the crank pin.
